(57) **CLAIM**

I claim the ornamental design for a golf putting stroke training device, as shown and described.

DESCRIPTION

FIG. 1 is an isometric view of a golf putting stroke training device showing our new design;
FIG. 2 is a top plan view thereof;
FIG. 3 is a left side elevation view thereof;
FIG. 4 is a right side elevation view thereof;
FIG. 5 is a bottom plan view thereof;
FIG. 6 is a front side elevation view thereof; and,
FIG. 7 is a rear side elevation view thereof.
